Inventor.

Amos Shepard

United States Patent Office.

AMOS SHEPARD, OF SOUTHBURG, CONNECTICUT.

Design No. 4,288, dated August 9, 1870.

DESIGN FOR A SAUSAGE-FILLER.

The Schedule referred to in these Letters Patent and making part of the same

I, AMOS SHEPARD, of Southington, in the county of Hartford and State of Connecticut, have invented and produced a new and original Design for a Sausage-Filler, of which the following is a specification.

My design consists of a straight cylinder, provided with a cone-shaped end piece, from which cone projects a cylindric nozzle, at an angle of forty-five degrees to the cylinder.

The device is mounted on legs, so as to bring the nozzle in a horizontal position, while the cylinder stands at an angle of forty-five degrees.

In the accompanying drawings—

Figure 1 is a side elevation of my design; and

Figure 2, a top view of the same.

The lever and plunger for forcing the meat through the cylinder are not shown.

A designates a straight cylinder, which, being cast in halves, is provided with lugs, *a a*, through which lugs are the rivets, *b b*.

B designates a cone-shaped end-piece, attached to the lower end of the cylinder A. The taper of the cone B is such that its sides stand at an angle of about forty-five degrees to the sides of the cylinder.

Projecting from the cone B is a cylindric nozzle, C, which also stands at an angle of forty-five degrees to the cylinder, and with its lower side on a line, or very nearly so, with the under side of the cone B, while the upper side of said nozzle is at or about right angles to the upper side of said cone.

From the nozzle C projects an ordinary tin tube, D.

The legs E E support the cylinder A at an angle of about forty-five degrees, while the nozzle is horizontal.

This design is one of utility more than ornament, as it brings the nozzle in such position to the cylinder that the meat can be forced through the same with little resistance.

I claim as my invention—

The design for a sausage-filler, consisting essentially of the straight cylinder A, cone-shaped end-piece B, and nozzle C, all formed, combined, and arranged substantially as shown and described.

AMOS SHEPARD.
